UNITED STATES PATENT OFFICE.

FRANZ F. PETERS, OF MILWAUKEE, WISCONSIN.

PICTURE-FRAME.

SPECIFICATION forming part of Letters Patent No. 356,328, dated January 18, 1887.

Application filed August 5, 1886. Serial No. 210,080. (No model.)

To all whom it may concern:

Be it known that I, FRANZ F. PETERS, of Milwaukee, in the county of Milwaukee and in the State of Wisconsin, have invented certain new and useful Improvements in Picture-Frames; and I do hereby declare that the following is a full, clear, and exact description thereof.

My invention relates to picture-frames; and it consists in such an article made from a single piece of molding without waste, all the pieces necessary for such article being joined in such a manner that in their united positions they thoroughly match each other and form a frame wherein the corners are offsetted from the sides, as will be hereinafter described with reference to the accompanying drawings, in which—

Figure 1 represents a front view of a picture-frame constructed according to my invention, and Fig. 2 a detail perspective view of one corner thereof.

Referring by letter to the drawings, A represents the several main pieces or sides of my frame, each having its respective ends cut on two opposite-angle faces, *a b*, of forty-five degrees each, the faces *a* of said parts meeting to form miter-joints, *c*, at the inner corners of the frame. To each face of the angles *b*, I miter-join a narrow piece, C, of the molding, so cut that when thus joined its beads and grooves will match those of the corresponding main or side piece, A, but be at right angles thereto, thus forming an offset at the outer corners of the frame.

In order to square up the corners and complete the frame, I cut from the molding a series of right-angle triangle pieces, D, and miter-join the same together in pairs to make blocks that have their outer edges in the form of a right angle, and which I miter-join to the pieces C, that have been previously united to the parts A.

When the several pieces of molding have been joined as above described, the beads and grooves thereon will all match and the parts C D of each corner unite at *d* to form a common center. In case the inner edge of the molding is concave the common center of each corner will be in the form of a concave depression, and should such edge be plain the de-

pression would correspond; but if said edge be convex these centers would be elevated.

In the manufacture of frames according to my invention it requires twenty pieces for each one thereof, these pieces being as follows: four main or side pieces, A, eight of the narrow ones, C, and four each of the right-angle triangle ones, D, all being joined together and held in place by any suitable means. These pieces are all cut from a single piece of molding without waste; or, in other words, I employ the right-angular pieces that are cut from the ends of the molding in the operation of making frames in the usual manner, these pieces being utilized to square up the offsetted corners, as above described.

By the construction above described I not only am enabled to utilize all the molding, but at the same time produce a frame that is very ornamental in its appearance, besides being stronger at its corners, while I am also enabled to do away with the separate pieces that are ordinarily employed as corner ornaments, these last-named parts being usually made of plaster-of-paris or other frail material that is easily broken or bent, thereby marring or otherwise injuring the beauty and value of said frame.

While I have described my invention as constructed from molding having its face provided with beads and grooves, it is obvious that any picture-frame molding may be as readily employed.

Having thus fully described my invention, what I claim as new, and desire to secure by Letters Patent, is—

1. A picture-frame having the corners thereof offset from the sides, said corners and sides being of the same molding and so matched and joined as to form a continuous article, as set forth.

2. A picture-frame made from twenty pieces of the same molding so cut and joined as to form a continuous article having offsetted corners, as set forth.

3. A picture-frame having its side or main pieces provided at their respective ends with opposite-angle faces, a series of narrow pieces joined to the several outer faces of the main ones to form a right angle to each of the latter and a series of right-angle triangle pieces joined

together in pairs to form blocks having right-
angular outer edges, and said blocks joined to
opposing narrow pieces at each corner of the
frame, substantially as and for the purpose set
forth.

5 In testimony that I claim the foregoing I
have hereunto set my hand, at Milwaukee, in

the county of Milwaukee and State of Wisconsin,
in the presence of two witnesses.

FRANZ F. PETERS.
